(76) Inventor: **Henry Burden**

Henry Headen,

Letters Patent. Patented May 26. 1825

The Schedule referred to in these Letters Patent, and making part of the same, containing a description in the words of Henry Headen himself, of his improvement in the manufacture of wrought rails and spikes, solely by the aid of machinery.

I make use of a fixed frame of cast or wrought iron, the side pieces and ends being four inches square, longer or shorter as may be deemed necessary. The one iron in operation is four feet long and eighteen inches wide; inside at the one end of the frame is fixed the crank shaft, on which is thrifty wheel and pulley, from which a belt or other gearing may be attached to give motion to the machine. About the middle of the fixed frame is a toothed wheel, a part of which is under the other projection above the frame through which the rollers move on their centers or nail which rolls out the nail. On the inside of the fixed frame are four bushes in which the moving frame slides forward and back ward, these bushes, two of which are movable (one side being, in grooves in the fixed frame by means of screw bolts passing through the sides of the fixed frame, to make the moving frame play tight or easier) may require the moving frame may be made of cast or wrought iron, - the one iron in operation is cast iron; two feet long and eighteen inches wide; setting on the bushes at the four corners; - on the end of said frame is attached the pitman or connecting rod which, being connected with the crank, gives motion to the machine. The side of said frame is formed a straight track seven inches long, having pegs in it to give motion to two rollers which are edge on set out the nail. To the same side of the moving frame to which is fastened in a place forward of the side steel between which the rod is fastened. This steel is about one inch thick, three inches wide and the length of the nail required, is moved as necessary by screw bolts on the sides and ends. Opposite this steel about two inches distant is a moving lever, one end of which is fastened through a mortice by means of a bolt or pin in the one end of the moving frame. In this lever is a place for the other side steel, the dimension of which is the same as the one above described, and is fastened by bolts in a similar manner. By means of these bolts, the side steels may be moved so as to admit the rod and swedged or rollers that roll out the nail. Parallel with the side steels and on a line with the center of the lever is the header, the end of which being set at the distance of the thickness of the head from the ends of the side steels. This header is made in a mortice, or groove by a crested lever of cast or wrought iron, the end of which being fastened by a pin or belt passing through into the moving frame and fastening at right angles with the header until the end indents the side of the fixed frame, on which is a wedge, so that when the moving frame is put in motion, the wedge that is fixed on the fixed frame, pushes or pins the end of the header lever as it passes along, by which means ^{the header} is moved forward just enough to sweep the head sufficiently, - which is always governed by the angle and shape of the wedge. Through the header there will be

it includes the header is a screw bolt, the end of which bears against the end of the header, which by turning, gradually lessens the thickness of the head of the nail. The moving lever in which one of the side steels is fastened is given motion by a similar wedge to that of the one on the other side of the fixed frame, which gives motion to the header. This wedge is so shaped that when the lever opens along, as it is moved by the moving frame, it closes as the rod passes between the side steels & remains so until the nail is rolled out, where, by means of the wedge tapering at the other end, the lever opens and lets the nail drop. The rollers attached to in the passing description, one of which being placed between the two posts which is connected with the fixed frame, this roller being fixed on moveable centers, which centers pass through the lower end of the post under the frame fastened by screw bolts parallel to this roller, and ten inches above, lays the other roller, fastened by means of moveable centers passing through the upper ends of the posts, these centers being fixed by screws in the same manner as the under centers are. Connected with these rollers is an open mortise on one end of each wherein is fastened by means of screw bolts, two segments of a circle made of cast or other steel, whose radius is five inches and finishing in the same length of the side steels and nail intended; these segments or wedges the edges of which being precisely the same thickness as the nail intended are each separately fastened perpendicular to the horizon; with these edges or peripheries facing each other, these segments or wedges being placed by means of screw bolts, so that their edges ... play readily between the two side steels leaving the same distance between their edges as the thickness of the nail intended.

The iron being slit into rods of a suitable size; the thickness of which, being always the same as the nail intended, and as much wider as is found necessary to prevent the nail from slipping between the wedges and side steels while the head is flattening on. The rod being heated is admitted into the machine on edge, the end of which bears close to the header end is confined on the sides by the two side steels which are fastened in the moving frame so that the iron cannot escape, the two rollers or wedges being put in when by the hand through the moving frame gradually tapering the nail to the point where the two wedges meet together and cut off the nail; in this situation the nail remains between the two side steels in the sides and header in front, when the moving lever in which is fastened one of the side steels opens and will let the nail drop.

Secondly, I claim as my invention and improvement the following method of making wrought nails or spikes, in lieu of the side steels formerly described, between which the rod or nail is confined, while the dredges or rollers shape or roll out the nail, take two wedges or rollers, similar to those perpendicular ones which will the nail having the same thickness of the side steels, one of these dredges or rollers being placed (here centrally) on each of the vertical or

These side wedges or rollers perpendicular to each other being fastened by means of tenons into cast iron rollers which stand perpendicular to the horizon fastened by mortise centers at both ends. These wedges or rollers being moved together with the vertical wedges or rollers by means of gearing to the moving frame; then the rod being heated is introduced between the two horizontal wedges or rollers on the sides of the vertical or perpendicular wedges or rollers on the upper and under sides and head in front, all of which being put in motion by the crank shaft through the moving frame formerly described, by which means the rod is gradually tapered on the sides, by the side wedges or rollers, while the vertical or perpendicular wedges or rollers taper from the upper and under side until it is entirely cut off at the point, the head being put on in the manner above described. In this manner, nails may be made tapering from all the four sides terminating in points as those made under the hammer. Under the first head described the nails are only tapered from two sides by two vertical or perpendicular wedges or rollers while the nail is confined between the side stiles.

Thirdly, I claim as my invention and improvement to the following method for making wrought nails or spikes. Take two rollers of cast iron wrought iron case hardened, steel, or any other substance which may be considered suitable for the purpose. These rollers are first turned smooth to any given size, for a quarter of an inch they are six inches in diameter and twelve inches long, their circumferences being eighteen and one-eighth inches, scarcely with these rollers I calculate to make ten spikes iron for nails of any given size. Then grooves into the rollers for every sized nail intended to be made, the width of these grooves being precisely the width of the thickness of the nail intended, and a little deeper. On the other roller I turn down having projections, or tongues, similar to those of the grooves in the other roller divided accurately, so that each projection or wedge, will fit exactly into each respective groove; thus the recent spikes are turned down a sufficient depth so as to admit these projections or wedges to be inserted in their respective grooves. Then divide the circumference of each projection or wedge into an equal number of distances as there may be thickness of nail intended, for example, suppose a six penny nail to be two and five-eighths inches long, turn off the work, stand round the periphery of the roller, then divide the projection into seven equal parts; take a file and reduce the projection at one of these points enough down so as to be equal to the difference between the size of the nail at the head, and that of the point, thus gradually lessening the quantity taken off, until you arrive at the next point or mark, diminishing at nothing, which will cause shape the top and point off the nail when in operation. Thus having formed the projection and groove, let us form a true taper to the nail, file or reduce the remaining top spaces of the projection or wedge, fitting it to the nail head & the points alternately together, thus the revolution of the roller will make seven nails without heads, the iron being slit into rods of various sizes, is heated, and after passing through the grooves or wedges is formed into as many nails or points as they are in length of nails. These rods after being rolled or wedged are cut by means of shears at the head and point, these points or nails being heated in a furnace may be headed by hand, or in the usual way of heading out nails by the aid of machinery.

Fourthly. I claim as my invention and exclusive right all the combinations and improvements described under the three former heads, and further may be an infinity of combinations, or methods combined, whereby wrought nails or spikes may be made by the aid of machinery (the principle being given) which it particularly intended that whether they are wrought upon, or ground rollers having thin surfaces or grooves so shaped as to give the required taper to the nail, at each length of nail as is described under the third head. Or whether sections or segments of these rollers or swedges may be taken and fastened into rotating rollers or wheels. Finishing the nail or spike in the operation, as is described under the first head, after any of the above described, or any other combination of said methods as the nail or spike is shaped by means of rolling or rotating, ready for rolling or sections of rollers where preference or convenience so directs as to give the desired taper to the nail or spike while it is in contact with said rollers or swedges.

Using the first method or wrought nails or spikes in this manner, I claim the same, using exclusive right and privilege. In all the methods above described, the wrought nails or spikes are not passed smaller under the head than the body of the nail, but with full size similar to those made by the hand. That is to enter such hole in the end of the head which makes the head of the nail or spike high on the center as those made by the hammer.

This latter invention, I do not claim farther than the application to my method of making nails.

George Burdin.
